WATER-COOLED GUIDE DISK

Samuel E. Diescher, Pittsburgh, Pa., assignor to
Diescher Tube Mills, Inc., Pittsburgh, Pa., a
corporation of Delaware

Application October 19, 1933, Serial No. 694,255

15 Claims.

(Cl. 80—41)

My invention relates to water-cooled guide disks, and particularly to such guide disks as are employed in connection with cross-roll mills.

In the construction and operation of cross-roll mills, such for example as those shown and described in my Patent No. 1,870,209, granted August 2, 1932, tubular blanks on mandrels are passed between two cross rolls the axes of which are inclined to each other and to the pass line of the tubular blanks. The tubular blanks are caused to move through a helical path by the action of the cross rolls.

Guide disks that are mounted on axes at right angles to the pass line between the cross rolls limit the outward bulging of the metal caused by the action of the cross rolls and thereby control the outer diameter of the resulting tube. The guide disks are preferably driven at a higher peripheral speed than the longitudinal travel of the tubular blanks, whereby the transverse friction between the tubular blanks and the guide disks is materially reduced and the flow of the metal due to compression between the cross rolls and the mandrel is directed longitudinally and the blank is pulled forward in the pass.

The almost continuous operation of the guide disks in contact with highly heated metal when the mill is operating at a high rate of production and particularly at peripheral speeds much higher than the longitudinal travel of the metal causes the guide disks to become highly heated, with the result that the diameters of the disks may vary somewhat in accordance with the variations in their temperature and the diameters of the tubes may have corresponding variations in the opposite direction.

It will be appreciated that, as the temperatures of the guide disks increase, their diameters may also increase with the result that the space between the disks is shortened and the diameter of the resultant tubes, which is controlled by the spacing of the guide disks, may be diminished. Similarly, if the guide disks have been adjusted at their higher temperatures for producing tubes of the proper diameter and the disks are cooled, as might occur during a breakdown or stop for repairs or for other reasons, the shrinkage of the guide disks by cooling will cause the tubes subsequently produced to be larger in diameter than those rolled by the guide disks while the latter are at their higher temperatures. This condition will obtain until the disks are again at their higher temperatures.

In accordance with the present invention I provide guide disks for cross-roll mills that have

water-cooled systems whereby the temperature variation and the corresponding expansion and contraction of the guide disks may be limited within such ranges as not to detrimentally affect the sizes of the tubes that are rolled thereby.

I provide an efficient arrangement for supplying cooling water to the interiors of the rapidly rotating guide disks while in operation, and also for the escape either of steam or of highly heated water in order to dispose of such heat as may be necessary to retain the guide disks within a pre-determined maximum temperature.

The details of my invention will be described in connection with the accompanying drawings, in which Fig. 1 is a face view of a cross-roll mill embodying guide disks constructed in accordance with my invention and looking in the direction of feed of a blank through it, a mandrel and a blank being shown in transverse section at the throat of the pass; Fig. 2 is an enlarged transverse cross-sectional view of one of the guide disks taken on line II—II of Fig. 3; and Fig. 3 is a face view of the guide disk of Fig. 2.

The mill illustrated in Fig. 1 comprises a pair of oppositely disposed cross rolls 1 and 2 having their axes inclined to each other and to the line of feed of a blank between them. Disposed between the cross rolls and on opposite sides of the pass between them is a pair of adjustably mounted grooved guide rolls or disks 3 and 4, arranged on horizontal axes and adapted to be driven in any suitable or usual manner, as by wobblers, not shown. In the pass formed between these two pairs of rolls is shown a cylindrical mandrel 5 within a tubular blank 6 undergoing reduction in wall thickness and elongation by the combined actions of the rolls.

While the structure of the disks 3 and 4 and the manner of mounting and the details of associated parts are substantially identical, the details of the lower guide disk 4 only are shown by way of example. The disk 4 is provided with a shaft 7 that is suitably splined as at 8 for attaching driving connections thereto. At the opposite end of the shaft 7 is a thrust bearing 9 at the outer end of which is a hood 10 engaged by a bar 11. The lower portion of the hood is provided with an opening or slot 12 through which extends a feed pipe 13 for supplying cooling water to the guide disk 4 in a manner to be presently described.

Reference may now be had to Figs. 2 and 3 which illustrate in enlarged detail the construction of the guide disk 4. The shaft 1, only a portion of which is shown, is provided with an enlarged cylindrical portion 15 to constitute a

seat for the guide disk 4. The right end of the shaft 7 as viewed in Fig. 2 is provided with a bore 16 extending from the outer end of the shaft into the plane of the disk 4.

- 5 The bore 16 is provided with a lining tube 17 of brass or other suitable material within which is a feed pipe 18 preferably of steel for supplying water to the interior of the disk. The feed pipe 18 is connected to the outer end of the pipe 16. 10 The pipe 18 is closed at its inner end. The pipes 17 and 18 which rotate relatively to each other may have a relatively close fit in order to minimize seepage in case no stuffing box is provided at the outer end of the shaft 7. Such seepage 15 will be substantially eliminated if a stuffing box 19 illustrated in Fig. 2 is employed.

The pipe 17 preferably does not extend to the inner end of the bore 16 and thereby provides an annular space 21 surrounding the end of the pipe 18 and which extends to the inner end of the bore 16. The pipe 18 is provided adjacent its inner end with a plurality of radial openings or discharge ports 22 that communicate with the annular space 21.

- 25 The shaft 7 is provided with eight radial holes or passages 23 that are in substantially the same plane as the openings 22 and communicate with the annular space 21. Surrounding the enlarged portion, or seat, 15 is the hub portion 24 of the 30 guide disk and which has extending radially therethrough passages 25 that are in alignment with the passages 23 in the shaft 7.

Extending around the outer periphery of the hub 24 is an annular member the inner part of 35 which is a ring 26 having an inwardly extending flange 27 that is bolted to the hub 24 by means of a series of bolts 28 that are eight in number although any suitable number may be employed. The ring 26 is similarly provided with eight 40 radially extending passages 29 that register with the passages 25 of the hub.

- Surrounding the ring 26 are two annular wall members 31 and 32 that are inclined toward each other in the direction toward their outer edges 45 upon which they support a relatively narrow and radially thin rim 33. Preferably the annular members 31 and 32 are welded to the ring 26 and to the rim 33. The latter is most desirably of 50 forged steel of the lowest possible coefficient of expansion that can be welded in order to minimize changes in dimension with variations in temperature. The rim 33 is most desirably provided with an outer coating 34 of an alloy that is 55 highly resistant to abrasion and wear.

The aligned passages 23, 25, and 29 constitute inlet passages for cooling water into the annular chamber 35 formed by the members 31 and 32 and the ring 26 and the rim 33. Outlets from the 60 chamber 35 are provided as shown in the lower portion of Fig. 2 and indicated in dotted lines in Fig. 3. Each outlet comprises a short radial hole 36 extending from the chamber 35 radially inward to connect with a transverse passage 37 65 through the ring 26 the ends of which passage are open to the atmosphere.

- As best shown in Fig. 2 each outlet opening 36 is partially covered by a baffle 38 of substantially V-shape the outer portions of which are 70 slightly spaced from the inner surfaces of the wall members 31 and 32. The baffles 38 serve the purpose of preventing water from flowing directly from the chamber 35 into the openings 36 when the guide disk is in motion, and they also serve to 75 reduce the amount of entrained water that such

steam as may escape from the outlet port can carry entrained into the openings 36.

It may be assumed that the cross-roll mill of Fig. 1 is being driven at its normal operating speed and rolling tubular blanks on mandrels to 5 reduce the wall thickness of the blanks and elongate them, by passing them between the cross rolls 1 and 2 and the guide disk 3 and 4. The guide disk 3 and 4 will be supplied with cooling water through feed pipes such as pipe 18 of Fig. 1 10 into the interior of their supporting shaft for distribution into the annular chamber 21 of each guide disk.

Water flows substantially equally in all directions through the aligned inlet passages 23, 25, 15 and 29 into the chamber 35 and is thrown outwardly against the rim 33 by the centrifugal force of the rapidly rotating disk and by the inclined sides of the members 38 which deflect the water to the outer portion of the chamber 35 and 20 against the rim 33. Water entering the chamber 35 is thus prevented from flowing along the inner wall of the chamber and out through the outlet openings 36 unless the chamber is filled 25 with water.

When the rim 33 is in contact with the highly heated tubular blanks during the rolling operation, heat is conducted to the rims from the tubular blanks and to some extent from the rim to the wall members 31 and 32, and heat is also 30 generated in the rims by reason of the frictional engagement of the blanks and the rapidly rotating guide disks. Heat from the rim and wall members passes to the water in the chamber. In case steam is generated it will collect on the inner surface of the chamber 35 because the water is thrown outwardly by centrifugal force. The steam will flow outwardly through the outlets 36 and 37 and escape into the atmosphere to carry away the excess heat that has been imparted to the rim 33. If the supply of water through the feed pipe 18 has been sufficiently rapid, hot water may escape through the outlet ports before steam is formed.

The flow of cooling water may be regulated as 45 desired in order to insure that the temperature of the guide disk and especially of the rim does not exceed a maximum limit that is desirable in connection with the operation of the mill. If it is desired that only steam flow out through the 50 outlet ports, adjacent the pass of the mill, the supply of cooling water will be limited to such rate as will insure the formation of steam. If the supply of cooling water is suitably increased, the rim may be maintained at such low temperature 55 that steam does not form, whereupon water flows from the ports 37.

When the mill is brought to rest and the supply of cooling water for the guide disks is cut off, the major portion of the cooling water in 60 the chamber 35 will escape through the outlet openings in the lower portions of the guide disks in their stationary position. It is advisable therefore to rotate the guide disks and to supply them with cooling water prior to the rolling 65 of tubular blanks thereby.

The advantage of water-cooled guide disks for cross-roll mills in accordance with my invention is that the temperature of the guide disks may 70 be suitably controlled within such limits as to prevent undue variations in the diameter of the guide disks. Uniformity in the diameter of the guide disks permits a corresponding uniformity in the diameter of the tubes produced by the 75.

cross-roll mill of which the guide disks are an important part.

The reduction in temperature of the disk surfaces in contact with the tubes eliminates the rapid wear of the grooves that would occur at the higher temperatures.

The foregoing and other advantages will be apparent to those skilled in the art of constructing and operating apparatus of the same general character as the guide disks of my invention.

I claim:

1. A guide disk for cross-roll mills, comprising a hub portion, and a circumferential rim portion adapted to be heated by frictional engagement with hot surfaces, and having a continuous annular chamber of uniform cross-section extending around said disk adjacent said rim portion, passages for supplying cooling fluid through said hub portion to said chamber, and outlets for the cooling fluid opening from inner portions of said chamber.

2. A guide disk for cross-roll mills, comprising a hub portion, a circumferential rim portion, a liner formed of a different metal than the rim portion secured to the periphery of the latter and adapted to be heated by frictional engagement with hot surfaces, an annular chamber the outer wall of which is constituted by said rim portion and which is so shaped as to take advantage of the forces developed by rotation of said disk to concentratedly apply a cooling fluid to the periphery of said rim portion, inlet passages for cooling fluid extending through said hub portion and communicating with said chamber, and outlet passages from said chamber.

3. A guide disk for cross-roll mills, comprising a shaft, a hub on said shaft, an annular member surrounding said hub and supported thereby, said annular member having two laterally spaced wall portions and a rim supported on the outer peripheries of said spaced wall portions to constitute an outer wall for a chamber between said spaced portions, a passage extending axially of said shaft, passages extending radially between the axial conduit and said chamber, and outlet passages from said chamber.

4. A guide disk for cross-roll mills, comprising a shaft, a hub on said shaft, an annular member surrounding said hub and supported thereby, said annular member having two laterally spaced wall portions and a rim supported on the outer peripheries of said spaced wall portions to constitute an outer wall for a chamber between said spaced portions, a passage extending axially of said shaft, passages extending radially through said hub and said member to connect the axial conduit to said chamber, and outlet passages extending inwardly from said chamber.

5. A guide disk for cross-roll mills, comprising a shaft, a hub on said shaft, an annular member surrounding said hub and supported thereby, said annular member having two laterally spaced wall portions and a rim supported on the outer peripheries of said spaced wall portions to constitute an outer wall for a chamber between said spaced portions, a passage extending axially of said shaft, passages extending radially through said hub and said member to connect the axial conduit to said chamber, and outlet passages each comprising a portion extending inwardly from said chamber and a portion extending laterally of said annular member and opening to the atmosphere.

6. A guide disk for cross-roll mills, comprising

a rim portion adapted to be heated, an annular cooling chamber of uniform cross-section adjacent thereto, inlet passages adapted to supply cooling fluid to the periphery of said chamber while the disk is rotating, outlet passages from said chamber, and means for causing cooling fluid to travel a tortuous path in said chamber to enter said outlet passages.

7. A guide disk for cross-roll mills, comprising a peripheral portion adapted to be heated, an annular cooling chamber of uniform cross-section formed in the disk proper adjacent said peripheral portion, inlet passages adapted to supply cooling fluid to said chamber while the disk is rotating, outlet passages from said chamber, and means for causing cooling fluid to travel a tortuous path in said chamber to enter said outlet passages, said means comprising a shield adjacent the openings of said outlet passages for deflecting liquid therefrom.

8. A guide disk for cross-roll mills, comprising a portion adapted to be heated, a cooling chamber adjacent thereto, inlet passages adapted to supply cooling fluid to said chamber while the disk is rotating, outlet passages from said chamber, and means for causing cooling fluid to travel a tortuous path in said chamber to enter said outlet passages, said means comprising a member having a non-radial surface for deflecting liquid toward said portion of the disk adapted to be heated.

9. A guide disk for cross-roll mills, comprising a portion adapted to be heated, a cooling chamber adjacent thereto, inlet passages adapted to supply cooling fluid to said chamber while the disk is rotating, outlet passages from said chamber, and means for causing cooling fluid to travel a tortuous path in said chamber to enter said outlet passages, said means comprising a member of approximately V-shape spanning each opening into said outlet passages.

10. A guide disk for cross-roll mills, comprising an annular rim formed of a different metal than the rest of the disk and adapted to be heated by contact with hot surfaces, two spaced annular wall members connected to said rim and extending inwardly therefrom, a ring connecting the inner edges of said spaced annular members to form a chamber for cooling fluid adjacent said rim, a hub for supporting said ring, inlet passages extending through said hub and said ring for supplying cooling fluid to said chamber, and outlet passages from inner portions of said chamber.

11. A guide disk for cross-roll mills, comprising an inner portion and an outer peripheral portion adapted to be heated by frictional engagement with hot surfaces, and having a continuous annular chamber of uniform cross-section extending around said disk adjacent said outer peripheral portion, a passage for supplying cooling fluid through the inner portion to said chamber, and an outlet for the cooling fluid opening from an inner portion of said chamber.

12. A guide disk for cross-roll mills, comprising a disk shaped roll mounted for rotation on an axially disposed supporting shaft, a wearing surface formed of an alloy highly resistive to abrasion secured to the periphery of said disk, an annular cooling chamber of uniform cross-section provided in said roll adjacent its periphery, means for supplying a cooling fluid to said cooling chamber to minimize the distortion strains due to temperature changes between said wear

- surface and the rolls, and means for discharging said cooling fluid from the cooling chamber.
13. A guide disk for cross-roll mills, comprising a hub, the sides of which are extended beyond the body proper thereof in spaced relation with each other to provide at its periphery a rim-cooling chamber, a work-engaging rim made of a different material than the hub secured to the peripheries of said spaced side walls and forming therewith an annular cooling chamber of uniform cross section, and means for supplying a cooling medium to and exhausting it from said cooling chamber.
14. A guide disk for cross-roll mills, comprising a hub, the sides of which are extended beyond the body proper thereof in spaced relation with each other to provide at its periphery a rim-cooling chamber, a work-engaging rim having a different coefficient of expansion than the hub se-

cured to the periphery of said extended side walls and forming therewith an annular cooling chamber of uniform cross section, and means for supplying a cooling medium to and exhausting it from said cooling chamber.

15. A guide disk for a cross-roll mill, comprising a hub, the sides of which are extended beyond the body proper thereof in spaced relation to provide a rim-cooling chamber, a work-engaging rim secured to said extended side walls and forming therewith an annular cooling chamber of uniform cross section, means for supplying a cooling medium to and exhausting it from said cooling chamber, and means for directing the flow of the cooling medium through said chamber in such a way as to provide substantially uniform transfer of heat from said rim.

SAMUEL E. DIESCHER.
